UNITED STATES PATENT OFFICE.

JOSEPH KAUFMANN, OF NEW YORK, N. Y., AND JULIUS E. MERGOTT, OF NEWARK, NEW JERSEY, ASSIGNEES, BY MESNE ASSIGNMENTS, TO FRIEDA KAUFMANN, OF NEW YORK, N. Y., AND SAID JULIUS E. MERGOTT, OF NEWARK, NEW JERSEY.

SAFETY-LATCH FOR DOORS, &c.

SPECIFICATION forming part of Letters Patent No. 367,146, dated July 26, 1887.

Application filed March 24, 1887. Serial No. 232,224. (No model.)

To all whom it may concern:

Be it known that we, JOSEPH KAUFMANN, of the city, county, and State of New York, and JULIUS E. MERGOTT, of Newark, in the county 5 of Essex and State of New Jersey, have invented certain new and useful Improvements in Safety-Latches for Doors, of which the following is a specification.

This invention relates to certain new and 10 useful improvements in that class of door-bolts which are so constructed as to permit of opening the door only a certain distance, so as to permit of seeing the person that desires to enter before opening the door altogether.

Bolts of this kind have been made and used 15 heretofore, but were of such construction that after the door had been opened partly to enable the person on the inside to see the person desiring to enter the door had to be closed 20 again before it could be opened altogether.

The object of our invention is to provide a 25 safety-latch of such construction that the door can be opened partly and locked in place while thus partly opened, and then, when desired, can be opened altogether by the person at the inside and without requiring the door to be closed before opening it altogether.

The invention consists in the combination, 30 with a latch pivoted on the door-frame and provided at the swinging end with a notch, of a plate on the door, which plate has a slot through which the latch can pass, and a pivoted catch on the plate on the door, which pivoted catch automatically locks the latch in 35 place when the door is partly opened.

The invention also consists in the combination, 40 with said latch and plate, of a lock in the door, said lock being provided with a bolt which can be passed into or through an aperture in the latch pivoted on the frame for the purpose of securely locking the latch when the door is partly opened, all as will be fully described and set forth hereinafter, and finally pointed out in the claims.

45 In the accompanying drawings, Figure 1 is a face view of our improved safety door-latch, parts being broken out and others in section, the door being closed. Fig. 2 is a perspective end view of the slotted plate on the door and

part of the edge of the door. Fig. 3 is a plan 50 view of our improved safety-latch for doors, parts being broken out and others in section.

Similar letters of reference indicate corresponding parts.

The latch A is provided at one end with an 55 eye, A', through which a pin, B, is passed, which is held in angle-clips C on the door-frame D, thus adapting said latch to swing on the pin B. It is evident that the latch can be pivoted or hinged in any other suitable manner on the door-frame. A spiral spring, E, surrounding the pin B, has one end fastened to the same and the other to the latch, said spring serving to throw the latch in the direction of the arrow a', Fig. 3. Any other suitable spring 60 65 may be provided for throwing the latch in the direction of the arrow a—that is, in the direction from opening for the door; but we prefer the construction shown. The latch A has its swinging end beveled, as at F, and adjacent to said bevel it is provided with a notch, G, in its upper edge.

A plate, H, provided with a rectangularly-projecting wing, J, is fastened on the door W in such a manner that the part H' of the plate 75 projects beyond the swinging edge of the door. The said part H' is provided with a vertical slot, I, the lower end of which is in communication with a slot, K, in the rectangular wing J of the plate H. The height of the slot I must 80 be slightly greater than the greatest height of the latch A. A catch, L, is pivoted on the plate H above the latch A, and is provided at one end with a handle-lug, M, and at the opposite end with a weighted head, N, of such a size 85 that it can pass into the notch G of the latch A. A lock, O, is held in the rim of the door, the key-hole of said lock being below that part of the plate H across which the latch A rests. Said lock O is provided with a bolt, P, which 90 can pass into a suitable aperture in the rim of the door-casing or through an aperture, R, in the latch A near the swinging end.

The operation is as follows: The latch A is passed through the slots I K of the plate H, 95 and when the door is closed said latch rests transversely over the plate H, and is held in place by the catch L, which is adjusted ver-

tically, the lower part extending transversely over the latch A, as shown in Fig. 1. When it is desired to open the door, the catch L is swung into the position shown in dotted lines 15 in Fig. 1, so that its weighted end rests upon the top edge of the latch. As the door is opened, the latch A swings into the position shown in Fig. 3, and its upper edge slides under the weighted head N of the catch L. When to the notch G arrives at the weighted head of the catch L, said head drops into the notch and locks the latch in place, and also locks the door and prevents the moving of the door toward or from the rim of the casing. The 20 door is thus opened sufficiently to permit the person on the inside to see and examine the person on the outside. If the door is to be opened entirely to admit the person on the outside, all that is necessary is to press down the 25 handle-lug of the catch L, so as to raise the head N from the notch G. By opening the door farther, the latch A is withdrawn from the slots I K of the plate H and swung into the position shown in dotted lines in Fig. 1 by the spring E. When the door is to be closed again, the latch A is swung toward the rim of the door and passed through the slots I K 30 of the plate H, and when the door is swung against the rabbet of the casing the latch A is swung automatically across the plate H, and then can be locked in place by the catch L, as shown in Fig. 1.

In case it is desired to lock the door in place when partly open, as shown in Fig. 3, and to 35 prevent a person on the outside from raising the catch L by means of a wire or other implement, the bolt P of the lock O is thrown outward, so as to pass through the aperture R

of the latch A, (shown in Fig. 3,) whereby the latch is locked in place. The lock O and its bolt P can also be used as a night-latch.

Having thus described our invention, we claim as new and desire to secure by Letters Patent—

1. In a safety-latch for doors, the combination, with a swinging latch, of a fixed winged plate on the door, which wing is provided with a slot through which the latch can be passed, and of a catch pivoted on said plate for engagement with the latch, substantially as set forth.

2. In a safety-latch for doors, the combination, with a swinging latch, of a spring acting on said latch and swinging the same in a direction from the door, a winged plate having slots 55 in the wing, said winged plate being fastened on the door, and a catch on said plate, substantially as set forth.

3. In a safety-latch for doors, the combination, with a casing and door, of a latch pivoted on the casing, and provided with an aperture, a winged plate on the door, which winged plate has a slot through which the latch can be passed, a catch on said plate, and a lock held in the rim of the door, the bolt of 60 which lock is in the same horizontal plane as the aperture in the latch, substantially as set forth.

In testimony that we claim the foregoing as our invention we have signed our names in presence of two subscribing witnesses.

JOSEPH KAUFMANN.

JULIUS E. MERGOTT.
